UNITED STATES PATENT OFFICE.

FRANKLIN B. HAYS, OF INDIANAPOLIS, INDIANA.

CARBURETER.

1,346,201.

Specification of Letters Patent.

Patented July 13, 1920.

Application filed August 14, 1916. Serial No. 114,885.

To all whom it may concern:

Be it known that I, FRANKLIN B. HAYS, a citizen of the United States, residing at Indianapolis, Marion county, and State of Indiana, have invented and discovered certain new and useful Improvements in Carbureters, of which the following is a specification.

My invention relates to carbureters and its object is to provide means whereby a body of air is drawn through a body of hydrocarbon liquid so that the air and liquid will be properly proportioned to provide a highly volatile explosive mixture and the invention also aims to provide a construction having means of a simple and effective character for controlling the passage of the air through the carbureter and regulating its volume and that of the auxiliary air and the escaping vapor.

With these objects and others in view, my invention is embodied in preferable form in the construction and arrangement herein-after described and illustrated in the accompanying drawings.

In these drawings, Figure 1 is a vertical section through the carbureter; Fig. 2 a horizontal section on the line 2—2 of Fig. 1; Fig. 3, a horizontal section on the line 3—3 of Fig. 1; Fig. 4, an outside view, partly broken away of the hydrocarbon liquid receiving chamber and Fig. 5, a vertical section on the line 5—5 of Fig. 1.

Referring to the drawings, 1 is an inlet adapted to communicate with a source of heated air and serving to admit a body of hot air to the carbureter which constitutes the primary air supply. In the primary air inlet pipe are provided a series of cold air inlets 2 adapted to be controlled by a valve 3 which consists of a circular ring having openings 4 adapted to register with and regulate the size of the openings 2 and which is limited in a range of movement by means of set screws 5 secured to the inlet plate and extending through slots 6 in the ring valve.

The inlet 1 leads to air chamber 7, the upper wall of which is formed by a partition 8 constituting part of the base of the carbureter and which is provided with a series of openings 9 having beveled or curved seats in which are adapted to be seated ball valves 10 which valves are adapted to be raised

from their seats to permit the passage of the air by the force of the suction impulse through the inlet and such valves are held yieldingly to their seats by means of a common retaining member consisting of a cap 11 carried at the upper end of a vertical movable stem 12, the lower end of which is threaded and engages a sliding block 13 against the upper end of which block or nut bears a spring 14, the upper end of which spring bears against the lower face of the cross partition plate 8, whereby the stem 12 and cap 11 are normally pressed downwardly with a yielding action so as to hold the ball valves to their seats with a yielding spring pressure. Above the valves there is provided an annular chamber 14, formed by and between the wall of the outer removable shell 15 of the carbureter and the wall 16 of an inner cylindrical body. The chamber 14 communicates by means of annularly disposed spaced openings 17 with an annular chamber 18. The chamber 18 communicates at its lower end by means of annularly disposed spaced openings 19 with an annular chamber 20 adapted to contain wire gauze, the object of which is to effectually break up the particles of liquid hydrocarbon as the air is drawn through the same. The chamber 20 communicates at its lower end with a fuel chamber 21 having a float 22 which fits against and is guided solely by the wall of the fuel chamber and which controls a lever 23 bearing against the upper face of an admission regulating needle valve 24 against which bears a small spring 25 and which needle valve is adapted to close or open the opening 26 leading to the admission pipe 27, through which gasolene or kerosene is adapted to be admitted.

The chamber 20 has an annularly arranged series of openings 28 in its upper wall which lead into an auxiliary air receiving and mixing chamber 29. This mixing chamber is provided with a circular rotatable body 30 having openings 31 co-operating with openings 32 formed in the wall of the carbureter to admit or exclude or regulate the admission of air into the auxiliary air chamber for the purpose of admitting the necessary quantity of diluting air according to atmospheric or other conditions. The auxiliary air valve formed by this rotatable body is operated by means of a

worm or screw 33, the screw being carried by a shaft 34 journaled in the wall of the carbureter.

Above the auxiliary air admitting chamber is mounted a liquid catching wire screen 35 which is adapted to prevent large drops of liquid fuel from being carried to the outlet and to effect a final subdivision of the liquid for the purpose of facilitating the intimate mixture and increasing the combustibility of the charge.

The outlet 36 of the carbureter is controlled by an oscillatory flat disk valve 37 having segmental ports 38 adapted to register with similar ports in the wall 39 of the carbureter shell. A handle 40 for operating this throttle valve through the medium of a rack and pinion is provided.

In the operation of the carbureter the gasoline, kerosene or other liquid hydrocarbon fuel will be fed through the inlet pipe 27 to the fuel chamber 21 and when the fuel has risen in the latter chamber to the level of the openings 19, the float 22 will operate to lift the lever 23 and close the valve 24, thus cutting off the admission of the fuel. The heated primary air drawn through the inlet 1, by the suction of the engine, will lift the valves 10 from their seats. Such valves owing to their spherical form will always seat themselves correctly and will not bind or stick. The cap 11 yields to the pressure of the valves and the air will be admitted to the annular chamber 14 and thence drawn down through the opening 17 into the chamber 18 where it will pick up the liquid hydrocarbon in the bottom of said chamber and pass into the chamber 20, where it will come in contact with a further body of liquid hydrocarbon, the air thus becoming carbureted. The liquid fuel is subjected to suction and it will be drawn up against the wire gauze in chamber 20, thus breaking the liquid into fine particles. The carbureted air then passes through this dividing and suspending wire gauze and out into the auxiliary air chamber. It will be seen that the air drawn through the carbureter meets a body of liquid hydrocarbon of a fixed quantity

which, is subject to suction and hence only that amount of the liquid fuel will be drawn forward to form a charge which the air is capable of absorbing, thus preventing an excess of the liquid being impelled through the outlet by the mere force of the induced draft of air as in those types of carbureters in which the hydrocarbon fuel is injected into a rushing column of air.

The location of the fuel chamber within the casing insures a supply of liquid even when the car is running uphill at a steep incline and the form and arrangement of the float valve avoids the use of complicated and expensive guiding constructions for the float.

Having thus described my invention, what I claim is:

1. In a carbureter a float, a needle valve operated thereby, a float chamber, a plurality of chambers one of which contains wire gauze connected to said float chamber so as to receive liquid hydrocarbon fuel therefrom, means for passing air successively through said plurality of chambers, an auxiliary chamber above said float chamber communicating with said gauze containing chamber, and means for by-passing part of the air through said auxiliary chamber.

2. In a carbureter a float, a needle valve operated thereby, a float chamber a plurality of chambers one of which contains wire gauze connected to said float chamber so as to receive liquid hydrocarbon fuel therefrom, means for passing air successively through said plurality of chambers, an auxiliary chamber above said float chamber communicating with said gauze containing chamber, means for by-passing part of the air through said auxiliary chamber, and an oscillatory valve for regulating the outflow of fuel from said carbureter.

In witness whereof I have hereunto set my hand and seal at Indianapolis, Indiana, this 29th day of June, A. D. nineteen hundred and sixteen.

FRANKLIN B. HAYS. [L. S.]
